UNITED STATES PATENT OFFICE.

WILLIAM RIGNEY, OF IRVINGTON, NEW JERSEY.

SELF-ADJUSTING WATER-GAUGE CONNECTION.

Application filed December 5, 1924. Serial No. 754,077.

This invention relates generally to water gauges, and particularly to improved means for connecting the same to boilers, as well as for mounting the glass therein.

The tapping of boilers to receive the connections for water gauges is often done by eye judgment rather than by accurate measurement, the result being that the axes of the tapped holes, with which the opposite ends of a water gauge are connected, are frequently disposed in either diverging or converging directions, or else the boiler is tapped at points greater or less than the distance required for the particular type of gauge. When this occurs, and when the water gauge is coupled at its upper and lower ends with the boiler nipples, the water glass is subjected to lateral tension, with the result that the glass is either broken in the installation thereof, or becomes broken at some subsequent time due to expansion or contraction. Furthermore, the glass under lateral tension can not be given a water and steam tight connection at its upper and lower ends.

It is an object of the present invention to provide means of a simplified and improved construction whereby the water gauge may be properly installed upon the boiler without danger of breakage of the glass either in its installation or at subsequent times from expansion or contraction, regardless of the fact that the boiler nipples may be disposed at improper angles or improperly spaced apart.

A further object is to provide improved packing means in connection with water gauges to compensate for inaccurate disposition of boiler nipples, and also to permit of the glass being properly applied and maintained in proper steam tight connection without tension at its respective ends.

With these objects in view, together with others which will appear as the description proceeds, the invention consists in the novel construction, combination and arrangement of parts, all as will be described more fully hereinafter, illustrated in the drawing, and particularly pointed out in the claim.

50 In the drawing:

Fig. 1 is a side elevation of a water gauge structure embodying my invention, the connection between the gauge ends and the boiler nipples being shown in section,

55 Fig. 2 is an enlarged end elevation of

one of the improved packing members or gaskets,

Fig. 3 is a vertical sectional view taken through the said member,

Fig. 4 is a similar view of the cooperating packing element, and

Fig. 5 is an end elevation of the element shown in Fig. 4.

The boiler 6 is tapped at 7 to receive the nipples 8 to be connected to the gauge, and these nipples are carried by valves 9 of the ordinary construction and for purposes well known. The tapping of the boiler at inaccurate distances for the gauge to be used, or with the taps disposed at improper angles, causes the nipples or pipes 8 to be disposed at angles as illustrated, probably in slight exaggeration, in the drawing. In the drawing, the position of the pipes or nipples 8, if the tapping of the boiler was on a true center, is indicated by broken lines at A, in order to more clearly show the inclination of the nipple.

The water gauge may comprise the usual upper and lower elbows 10 and 11, between which extends the water glass 12, which is connected to the said elbows by steam tight packing glands, and the glass may be inserted through the upper elbow by removing the plug 13 carried thereby. The lower elbow is equipped with the usual pet cock 14. The glass 12 is protected by a series of rods 15 disposed parallel to the glass and connected at their ends to the flange members 16 arranged parallel to each other upon the upper and lower elbows.

Each of said flange members is provided with an outstanding annular boss 17 concentric with the opening in its respective elbow to communicate with the water glass. Each boss has threaded exteriorly thereof a packing nut 18.

Each of the elbows 10 and 11 has an angularly disposed pipe section 24 thereby connected to the globe valve pipe or nipple carried by the boiler. The outer ends of said pipe portions are enlarged and are threaded exteriorly as shown to receive the internally threaded nut members 25. Each of the annular bosses 26 thus provided includes an internal plane seat 27 surrounding the bore of the pipe, and which receives a member 22 of the cooperating packing. The cooperating packing members or elements comprises an annular member 20 having an in-

terior passage 21, said member 20 is of substantially frusto-conical form and is formed of a compressible material. The other element comprises an annular member 22 having a central aperture and inclined walls 23 upon its interior, corresponding substantially to the inclination of the exterior walls of the element 20. The nut members 25 of the gland are loosely carried by the inner ends 10 of the nipple or globe valve pipes 8, and this inner end of the pipe has an out-turned flange 28 to retain the nut in position, and to be engaged by the inwardly extending flange 29 of the nut section 25. It will be 15 noted that the outer face of the nut member 25 defining the opening through which the valve pipe extends is bevelled or cut away as at 30, permitting the said pipe and nut to assume various angular positions with 20 respect to each other.

This construction permits of the boiler nipple members being connected to the pipes 24 of the gauge with the assurance of a steam and water tight connection regardless of angular variations which may exist between these members. By tightening the nuts 25, the flange 28 is drawn inwardly against the packing element 20, forcing the inclined face thereof tightly against 25 the similarly inclined cooperating face of element 22, thus wedging these elements tightly together so as to be proof against leakage. The flexibility or pliability of the

packing permits of this joint being properly effected without strain upon the pipe members 24 of the gauge, and without danger of distortion of the gauge glass 12. 35

From the foregoing it is apparent that I have provided packing elements for use in connection with water gauges and gauge 40 mountings which are of extremely simple construction, which may be assembled properly without the exercise of special skill or knowledge, and which will accomplish the desired results in a facile manner. 45

Having thus described my invention, I claim:

In an adjustable union for a water gauge structure, pipe sections approximately aligned with each other, the section adjacent the gauge having a faucet end provided with a cylindrical counterbore defining a plane seat surface, the other pipe section having a flanged spigot end presenting a plane end face, a pair of compressible packing elements 50 nested in the said counterbore and presenting complementary conical abutting surfaces and plane end surfaces, and a union nut engaging said faucet end, and having an end flange embracing the rear of the 55 flange on the spigot end to clamp the latter into sliding engagement with the plane end surface of the outer packing element. 60

In testimony whereof I have signed my name to this specification.

WILLIAM RIGNEY.
